(57) **CLAIM**

The ornamental design for opposite facing dual seats, as shown and described.

DESCRIPTION

FIG. 1 is a perspective view of opposite facing dual seats showing my new design;

FIG. 2 is a front elevation view thereof, the rear being the same in appearance;

FIG. 3 is a left-side elevation view thereof, the right side being the same in appearance;

FIG. 4 is a top plan view thereof; and,

FIG. 5 is a bottom plan view thereof.

The broken lines are included to show features of the dual seating arrangement and form no part of the claimed design.
